UNITED STATES PATENT OFFICE.

CHARLES H. HAHN, OF NEW HAVEN, CONNECTICUT.

DESIGN FOR A TRAY FOR CIGARS, &c.

SPECIFICATION forming part of Design No. 27,601, dated August 31, 1897.

Application filed July 12, 1897. Serial No. 644,342. Term of patent 14 years.

To all whom it may concern:

Be it known that I, CHARLES H. HAHN, a citizen of the United States, residing at New Haven, in the county of New Haven and State 5 of Connecticut, have invented and produced a new and original Design for a Combination-Tray, of which the following is a specification, reference being had to the accompanying drawing, forming a part thereof.

10 In the drawing the figure thereof represents in perspective a view of my design.

The leading feature of my design, as shown in the drawing, consists of the representation of a recess or pocket or ash-receiver 1 at one 15 end, a corrugated or ribbed and channeled surface 2 adjacent thereto for holding cigars and matches adjacent to the ash-receiver, and a seat or socket 3 at the other end of the tray,

represented as having perforations 4, having a circular shoulder and groove 5, the same 20 representing a saucer or drip-socket for a glass or cup. The tray is represented also as being raised and supported upon side flanges or risers.

Having now described my invention, what 25 I claim as new, and desire to secure by Letters Patent, is—

The design for a combination-tray as herein shown and described.

In testimony whereof I affix my signature 30 in the presence of two witnesses.

CHARLES H. HAHN.
